UNITED STATES PATENT OFFICE

FRANK M. BEVERLY, OF MARION, OHIO.

MEDICINE-DISPENSER.

941,489.

Specification of Letters Patent. Patented Nov. 30, 1909.

Application filed April 24, 1909. Serial No. 491,977.

To all whom it may concern:

Be it known that I, FRANK M. BEVERLY, a citizen of the United States, residing at Marion, in the county of Marion and State 5 of Ohio, have invented certain new and useful Improvements in Medicine - Dispensers, of which the following is a specification.

My invention relates to medicine dispensers, and the objects of my invention are 10 to provide a simple, safe and inexpensive medicine dispenser; to so construct my improved dispensing device as to admit of a predetermined amount of liquid being drawn into a dropper tube; to provide improved 15 means for protecting said tube from breakage and to produce other improvements the details of which will be more fully pointed out hereinafter.

These objects I accomplish in the manner 20 illustrated in the accompanying drawing, in which:

Figure 1 is a central vertical section of my improved dispensing device, showing the mouth of the dropper tube closed, Fig. 2 is 25 a similar view showing the closure cap removed and inverted to form an air bulb section, and, Fig. 3 is a plan view of the construction shown in Fig. 2.

Similar numerals refer to similar parts 30 throughout the several views.

In carrying out my invention, I employ a bottle of suitable size such as is indicated at 1, said bottle being provided in its neck portion with a detachable cork or closure plug 35 2, which is adapted, as shown, to project above the bottle mouth. Through the center of the cork is formed a vertical opening 2^a which communicates with a dish-like depression 2^b in the upper end of the cork. 40 This dish-like depression forms a seat for the correspondingly shaped and flaring head or mouth-piece 3^a of a vertical dropper tube 3, said tube and head preferably being formed of glass or other transparent material. This tube extends downward, as 45 shown, through the opening 2^a of the closure plug 2 and has its lower termination tapered to form the usual medicine dropper terminal, said tapered end having a comparatively 50 small opening therein. The body of the tube 3 has molded, engraved or otherwise indicated thereon, graduation marks such as are indicated at 4, which marks are intended to indicate the amount of liquid 55 which may be contained within the tube.

When my improved dispensing device is

not in use, the upper end of the tube is closed by a central closure projection 5^a of a flexible dish-shaped member 5 which is adapted to fit within the head 3^a and the rim portion 60 of which is adapted to engage the rim of said tube head. When desired for use in drawing liquid into the tube from the interior of the bottle, the flexible cap or cover member 5 which is preferably of rubber, is 65 withdrawn from the position shown in Fig. 1 and inverted to the position shown in Fig. 2, the rim of said cap member engaging the rim portion of the tube head 3^a and the projection 5^a extending upward from the apex 70 of said cap.

It will be understood that the cap member 5 has its rim portion enlarged or thickened as indicated at 5^b and that said rim portion is of such circumference as to permit 75 of its being sprung or snapped over the rim of the cap member 3^a. When the cap is in the position shown in Fig. 2 of the drawing, it will be understood that by pressing downward on the cap, the air will be expelled 80 from the tube 3 into the bottle and that when the pressure on the cap is released, the liquid within the bottle, will be drawn into the tube from which it may be dispensed through the opening in the lower end thereof, by withdrawing said tube, together with the cork 2, from the bottle and again pressing downward on said cap.

It is obvious that a desirable amount of the fluid may be discharged through the 90 small opening at the end of the tube, in the usual manner of operating medicine droppers. However, owing to the employment of the graduation marks on the tube body, it will be understood that the amount of 95 liquid discharged from said tube may be regulated.

From the construction described, it will be seen that a simple and reliable medicine dispensing device is provided, which when 100 not in use may not only be closed at its upper end, but which will have its glass mouth-piece protected from danger of injury.

It is evident that the tube may have its head portion 3^a supported above the cork 2 105 if desired, by drawing the tubular body upward through the central opening of the cork.

What I claim, is:

1. In a medicine dispenser, the combination with a liquid holding receptacle, and a detachable cork therefor, of an open-end

tube extending through said cork, a flexible cap adapted to be detachably connected with the upper end of said tube, said cap having a central stopper projection which when the cap is inverted is adapted to close the upper end of said tube.

2. In a medicine dispenser, the combination with a bottle, a cork in the upper end of said bottle, an open end tube extending through said cork and having a flaring mouth formed therewith, of a flexible cap

having its edge portion adapted to detachably engage the mouth of said tube, said cap having a central closure projection as described.

15 In testimony whereof I affix my signature in presence of two witnesses.

FRANK M. BEVERLY.
